UNITED STATES PATENT OFFICE.

LEFFERD MERLE ALEXANDER HAUGHWOUT, OF PONCE, PORTO RICO.

SLIDING NAME-REGISTER.

1,368,144.

Specification of Letters Patent.

Patented Feb. 8, 1921.

Application filed January 28, 1920. Serial No. 354,579.

To all whom it may concern:

Be it known that I, LEFFERD M. A. HAUGHWOUT, a citizen of the United States, and a resident of Ponce, county of Ponce, 5 Porto Rico, have invented a new and Improved Sliding Name-Register, of which the following is a full, clear, and exact description.

This invention relates to registers, and has 10 reference more particularly to a sliding name register which indicates the presence or absence of the person indicated on the name plate.

An object of this invention is to provide a 15 sliding name register which can be stamped from a single sheet of metal and will be simple and cheap to construct.

A further object of this invention is to provide a name register which will indicate 20 the presence or absence of persons in large assemblies such as schools, churches, offices, hotels, and manufacturing concerns without necessitating a laborious roll call or personal inquiry.

25 A still further object of this invention is to provide a sliding name register in which the names of all persons present will be contained in one column, and the names of those absent will be contained in another column, 30 so that the two groups can be distinguished at a glance.

Reference is to be had to the accompanying drawing forming a part of this specification in which it is understood that the drawing 35 is merely illustrative of two examples of the invention, and in which—

Figure 1 is an elevation of one form of my invention showing a plurality of sliding name plates.

40 Fig. 2 is a second form of my invention in which one sliding name plate is shown.

Fig. 3 is a section through Fig. 2 on the line 3—3.

45 Fig. 4 is a section through Fig. 2 on the line 4—4.

Fig. 5 is a perspective view of one of the catch plates removed from the holder.

Fig. 6 is a detail perspective view of one 50 end of the name plate.

55 Referring to the accompanying drawing by numerals, 10 indicates a plate of any suitable material which is provided with a plurality of offset flanges 11, and a plurality of offset fingers 12 which are adapted to slidably support a name plate 13 between

one of said flanges, and a pair of said fingers (see Fig. 1). These flanges and fingers may be stamped directly from the plate 10 so as to provide a cheap construction. The ends of the name plate 13 are bent 60 back on said plate to form lips 14, which are adapted to engage a card 15 bearing a person's name or any other desired inscription and are also adapted to normally engage the finger 12 and prevent said name 65 plate 13 from being completely withdrawn. One end of the name plate 13 is cut away to make a recess 13^a which has the shape of the finger 12 so that when it is desired to remove the plate 13 to change the name, the 70 finger 14 may be raised slightly with any sharp pointed instrument so that the finger 14 may be moved past the finger 12 thus allowing the plate 13 to be removed. The card 15 may be covered by a sheet of some 75 transparent material such as celluloid if so desired.

When the name plate 13 is translated to a position farthest to the right as shown in Fig. 1, the word "Out" inscribed on the 80 plate 10, is covered by said name plate, and the word "In" inscribed at the left is uncovered. When the name plate 13 is translated to a position farthest to the left, the aforementioned conditions are reversed, and 85 a person is shown to be absent. In the modification shown in Fig. 2, the plate 10^a is secured to any suitable support 16 by means of fasteners such as tacks or screws 17. This plate 10^a carries flanges 11^a similar to flanges 90 11 which engage the name plate 13. This sliding name register is specially advantageous for use in schools, churches, offices, hotels, manufacturing concerns, etc., where a person may slide his name plate to the 95 proper position as he enters or leaves the building. Thus at a glance a person can determine which of the persons are present and which are absent, as the names of two groups of people occur in separate columns 100 on the register.

I would state in conclusion that while the illustrated example constitutes a practical embodiment of my invention, I do not limit myself strictly to the mechanical details 105 herein illustrated, since manifestly the same can be considerably varied without departure from the spirit of the invention as defined in the appended claim.

Having thus described my invention, I 110

claim as new and desire to secure by Letters Patent:

A sliding name register comprising a plate, a plurality of offset flanges formed on said plate, one or more name plates slidably secured to said plate by said flanges, a lip formed on each end of said name plate

adapted to normally engage said flanges and prevent the withdrawal of said name plate, and a recess formed near the end of each name plate adapted to permit the removal of said name plate from said plate when said name plate is flexed.

LEFFERD MERLE ALEXANDER HAUGHWOUT.
